US00D673962S

(12) **United States Design Patent**
Blaustein et al.

(10) **Patent No.:** **US D673,962 S**
(45) **Date of Patent:** **** Jan. 8, 2013**

(54) **USB DRIVE AND CARD READER WITH BODY**

(75) Inventors: **Evan Blaustein**, Brookline, MA (US);
Lillian Chan, Boston, MA (US);
Benjamin N. Huyck, Chicago, IL (US);
Robert E. Miller, III, Lombard, IL (US)

(73) Assignee: **MIMOCO, Inc.**, Boston, MA (US)

(**) Term: **14 Years**

(21) Appl. No.: **29/404,630**

(22) Filed: **Oct. 24, 2011**

(51) **LOC (9) Cl. 14-02**

(52) **U.S. Cl. D14/480.2; D21/621**

(58) **Field of Classification Search** D14/411, D14/433, 435, 435.1, 436–438, 480.1–480.7, D14/484.1, 137, 155, 203.1–203.8, 240; D13/133, 146–147, 154; 710/300, 301; 439/131, 439/135–147; 361/679.31, 679.33, 679.4, 361/752; 711/100, 115; D21/621, 630; D3/271.3; D9/614; D11/160; 446/387

(57) **CLAIM**

The ornamental design for a USB drive and card reader with body, as shown and described.

DESCRIPTION

FIG. 1 is a perspective view of the USB drive and card reader with body.

FIG. 2 is a rear view thereof.

FIG. 3 is a front view thereof.

FIG. 4 is a side view thereof.

FIG. 5 is the other side view thereof.

FIG. 6 is a top view thereof.

FIG. 7 is a bottom view thereof.

FIG. 8 is a perspective view thereof, with the tang in a closed position.

FIG. 9 is a top view thereof, with the tang in a closed position; and,

FIG. 10 is a bottom view thereof, with the tang in a closed position.

The broken line showings are included for the purpose of illustrating portions of the USB drive and form no part of the claimed design.

1 Claim, 7 Drawing Sheets
